UNITED STATES PATENT OFFICE

141,249

DESIGN FOR A DOLL

Lena Rugel Lamb, Dallas, Tex.

Application February 9, 1945, Serial No. 117,849

Term of patent 14 years

(Cl. D34—4)

To all whom it may concern:

Be it known that I, Lena Rugel Lamb, a citizen of the United States, residing at Dallas, in the county of Dallas and State of Texas, have invented a new, original, and ornamental Design for a Doll, of which the following is a specification, reference being had to the accompanying drawing, forming part thereof.

I claim:

The ornamental design for a doll, as shown.

LENA RUGEL LAMB.
